UNITED STATES PATENT OFFICE.

CYRUS C. JOHNSON, OF MCPHERSON, KANSAS.

OIL-BURNER.

1,238,780.

Specification of Letters Patent. Patented Sept. 4, 1917.

Application filed February 12, 1917. Serial No. 148,107.

To all whom it may concern:

Be it known that I, CYRUS C. JOHNSON, a citizen of the United States, residing at McPherson, in the county of McPherson and State of Kansas, have invented a new and useful Oil-Burner, of which the following is a specification.

The present invention appertains to hydro-carbon or liquid fuel burners, and aims to provide a novel and improved burner of that character applicable to ranges, stoves, and the like, whereby oil or other liquid fuel can be burnt instead of coal or other solid fuel, thereby to provide for a greater efficiency, economy and convenience, and eliminating ashes, dirt, soot, and other objections incident to the use of coal, as well as enabling the heat to be regulated.

It is also the object of the invention to provide a burner attachment for ranges, stoves, and the like, which can be readily applied, which is simple and inexpensive in construction, and which is durable, and satisfactory.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a front view of the range equipped with the present burner.

Fig. 2 is a side elevation of the range, portions being broken away and shown in section.

Fig. 3 is a plan view illustrating a modification.

Although the burner is illustrated as being applied to a range, it can be applied to a stove, furnace and the like. The range illustrated embodies a casing 1 having the fire pot 2, an upstanding back 3 for the warming chamber, an air draft controller or shutter 4 for an air inlet opening 4^a in that side adjacent which the fire pot 2 is located and below the grate 5 which forms the bottom of the fire pot. With the use of the present invention, the stove pipe damper, fire box and ash pan doors, and heavy grates, can be eliminated, and the hot water coil can be

used in the fire box, the same as in coal ranges and stoves if desired. The shutter 4 is separately provided with an opening 4^a to admit air even when the shutter is closed, and thereby avoid the choking or smothering of the flame.

The present burner includes a pan 6 constructed of metal, which may be cast, and which is capable of withstanding the heat to 60 when it is subjected. This pan is disposed within the fire pot and seats upon the grate 5, if there is one, and as illustrated, the pan or tray 6 is of rectangular outline. In applying the pan 6 within the fire pot, asbestos or other equivalent element is packed under and around the pan, to close the openings of the grate, if a grate is used, leaving openings under the pan for the upward flow of the air. The pan can be disposed 75 within the fire box with the grate removed, by placing asbestos cement around the pan between the pan and walls of the fire box, to support the pan and to close the openings around the pan. The flat bottom of the pan 80 6 is provided adjacent each end with an upstanding collar 7 providing air openings, and the central portion of the pan bottom is provided with a dome 8 midway between the collars 7.

An air flue 9 constructed of cast iron or other suitable metal, is disposed longitudinally above the pan, and is provided with downwardly curved ends 10 slipped or fitted upon the collars 7, and said flue is provided intermediate its ends with a depending outlet nozzle 11 concentrically above and adjacent to but spaced from the dome 8.

Liquid fuel, such as oil, is supplied to the upper surface of the dome 8 centrally thereof, and for this purpose, a fuel tank 12 is preferably attached to the upstanding back 3 of the stove, as at 13, and the fuel supply pipe 14 extends from the tank 12 to one side of the casing 1 and extends through 100 said side of the casing below the draft controlling shutter 4. Within the casing, the pipe 14 is provided with an upstanding nozzle 16 projecting through the grate and having its tip attached to the central portion 10 of the dome 8, whereby the surplus fuel will run down the sides of the dome onto the bottom of the pan. The pipe 14 has a suitable controlling valve 15 for regulating the flow of oil, to regulate the heat, and it is preferable to secure an asbestos or similar ring 17 upon the dome 8 surrounding the tip of the

fuel nozzle 16 to retain the fuel upon the dome.

In operation, fuel is supplied onto the dome 8 and ignited, and the air will pass upwardly into the flue 9 and downwardly from the nozzle 11 onto the dome, and the air and fuel will mix and spread in all directions, thus providing an annular fan-shaped flame. The surplus or overflow oil, if 10 the flow of the oil is too fast, will flow down the sides of the dome onto the bottom of the pan and burn up slowly without damaging effect. The upstanding collars 7 prevent the oil from flowing downwardly through the 15 air openings, even though the oil runs into the pan, and the dome 8 being raised provides for the proper flow of air and oil under all conditions, which is of advantage in connection with the flue 9 having the outlet 20 nozzle 11 associated with the dome 8. The flue 9 can be readily lifted from the pan for purpose of cleaning, examination or repair, and the burner is composed chiefly of two parts, viz., the pan 6 and the flue 9.

25 In Fig. 3, a circular pan 6' is illustrated,

having the collars 7 and intermediate dome 8, and this pan is adapted for use in a circular stove, and uses the same flue 9 as above described.

Having thus described the invention, what 30 is claimed as new is:

A hydrocarbon burner embodying a fuel-containing pan having a flat bottom and an upturned marginal rim, the pan bottom having upstanding collars within the rim and a 35 dome intermediate said collars, an air flue having downwardly extending ends fitted upon said collars and a depending air outlet nozzle intermediate its ends immediately above said dome, and a fuel supply pipe terminating at said dome for supplying fuel thereonto.

In testimony that I claim the foregoing as my own, I have hereto affixed my signature in the presence of two witnesses.

CYRUS C. JOHNSON.
